US00D939545S

(12) **United States Design Patent** (10) Patent No.: **US D939,545 S**
Oberkircher et al. (45) Date of Patent: **** Dec. 28, 2021**

(54) **DISPLAY PANEL OR PORTION THEREOF WITH GRAPHICAL USER INTERFACE FOR ENERGY MODULE**

(71) Applicant: **Cilag GmbH International**, Zug (CH)

(72) Inventors: **Brendan J. Oberkircher**, Cincinnati, OH (US); **Cory G. Kimball**, Hamilton, OH (US); **Matthew C. Miller**, Cincinnati, OH (US); **Jacob S. Childs**, Huntington Beach, CA (US); **Leonardo N. Rossoni**, Rahway, NJ (US)

(73) Assignee: **Cilag GmbH International**, Zug (CH)

(**) Term: **15 Years**

(21) Appl. No.: **29/704,617**

(22) Filed: **Sep. 5, 2019**

(51) LOC (13) Cl. **14-04**

(52) U.S. Cl.

USPC **D14/486**

Primary Examiner — John M Otte

(57) **CLAIM**

The ornamental design for a display panel or portion thereof with graphical user interface for energy module, as shown and described.

DESCRIPTION

The FIGURE is a front view of a display panel or portion thereof with a graphical user interface for an energy module. The outermost solid line shows a display panel or a portion thereof. The broken lines illustrate portions of the graphical user interface which form no part of the claim.
